UNITED STATES PATENT OFFICE.

GEORGE STANFORD WITHAM, JR., OF HUDSON FALLS, NEW YORK.

BEATER.

Application filed June 30, 1922. Serial No. 572,092.

My invention is an improvement in beater rolls, and mountings therefor, and relates particularly to directly driven rolls. In the usual arrangement of beater roll, some adjustment is necessary, between the roll and the bed-plate. The roll must be so mounted that it may be moved toward and from the bed-plate. To permit such adjustment, the roll has heretofore been connected to the motor indirectly, or by a flexible connection, so that adjustment of the roll will not interfere with the connection.

The doctor blade in the usual construction is arranged at an angle of 45° to the vertical, and touches the periphery of the roll at an angle such that unbroken stock passing through between the roll and the bed-plate may force the blade upward and push the curbing out of place. Furthermore, in the usual construction, the beater roll is heavy, rotates slowly and does not act to circulate the stock with the efficiency that is desirable.

In the present invention, I connect the motor directly with the beater roll, and so mount the parts, that the roll and motor may be adjusted together toward and from the bed-plate, without disturbing the connection between them and may be held in adjusted position with respect to the bed-plate. I provide an arrangement of doctor blade so mounted with respect to the roll, that unbroken stock passing between the roll and the bed-plate will be cut off cleanly and will be deflected outwardly from the roll.

I also provide a construction of beater roll wherein the blades or knives are integral with the body of the roll, and of a material permitting the roll to be of light weight without sacrifice of strength, thereby to allow the roll to be driven at a higher rate of speed, and I so arrange the blades or knives that they impart an active circulation to the stock in the beater. Thus, I attain an increased velocity in circulation of the stock, by the higher speed of the roll, and by the propelling action of the knives or blades.

In the drawings;

50 Figure 1 is a plan view of the improved beater roll directly connected with the motor, and having means for adjusting the

parts without interfering with the connection, with the covering removed.

55 Figure 2 is an end view,

Figures 3 and 5 are sections on the lines 3—3 and 5—5 respectively, of Figure 1,

Figure 4 is a front elevation.

In the present embodiment of the invention, the beater casing 1 is of usual construction, having the longitudinally extending partition 2, and the beater roll 3 is arranged at one side of the partition, being secured on a spindle 4, which is supported at its end by pairs of bearing brackets or pillars 5. The bearing brackets are arranged outside the casing, and the spindle is journaled at its ends in bearing bars 6 and 6^a, which are arranged between the members of the respective pairs, and are adjustable vertically with respect to the said members. The motor 7 for driving the beater roll, is connected directly with the spindle 4, by means of a frangible connection indicated generally at 8. The motor is mounted on the bearing bar 6, which is a substantially triangular plate, having its base arranged between the bearing brackets 5, and having its apex adjacent to the adjacent side of the beater casing. At its apex the bearing bar carries a bearing 9 in which the spindle 4 is journaled, and the frangible connection 8 is between the bearing 9 and the motor. The frangible connection is of usual construction, consisting of similar discs, which are connected by pins, adapted to shear under excess strain above a predetermined amount, to release or break the connection between the motor and the beater roll.

90 At the point where the spindle 4 passes through the beater casing wall to the motor, a packing gland is provided of rubber, or like flexible material, and so arranged that it does not interfere with the vertical movement of the spindle. The bearing 9 is a thrust bearing.

95 The bearing bar 6^a is mounted to move vertically between its bearing brackets or pillars 5 in the same manner as the bar 6. The pillars or bearing brackets 5 are hollow, being in the present instance open frames as shown, and each of the bearing bars is provided at each pillar or bearing

bracket with a nut 10, arranged to move within the pillar. Each nut is engaged by a threaded shaft 11 journaled in the pillar, all of the shafts being similar, so that when they are rotated, at like speed, the bearing bars will be moved together. Each shaft is provided at its upper end with a bevel gear 12, and the gears 12 of each pair of pillars are rotated by a cross shaft 13, each shaft 13 being provided with bevel gears 14 meshing with the gears 12. The shafts 13 are journaled in bearings 15, supported by the pillars, and means is provided for simultaneously rotating the four shafts. The said means is in the form of a shaft 16, which is journaled transversely of the beater casting, substantially parallel with the spindle 4, and the said shaft is supported by bearings 17, on the pillars. The shaft 16 is journaled below the shafts 13, and is connected to the shafts to simultaneously rotate them, by worm gear connections, each connection comprising a worm 18 on the shaft 16, and a worm wheel 19 on the adjacent shaft 13. Any suitable means may be provided for rotating the shaft 16, as for instance by means of a hand wheel 20 as shown. It will be obvious that when the shaft 16 is rotated by means of the hand wheel, the shafts 13 will be simultaneously rotated in the same direction, and the screw threaded shafts 11 will be turned to raise or lower the bearing bars 6 and 6^a. Thus both ends of the spindle will be simultaneously raised or lowered, the spindle axis remaining always horizontal.

The doctor blade in the usual construction is arranged at an angle of about 45° to the horizontal, and it touches the beater roll at an angle such that unbroken stock passing through between the roll and bed-plate may force the blade upward, and push the curbing out of place. In the present construction, I suspend the doctor blade indicated at 21 at a point such that when the free edge of the blade touches the beater roll, the blade will be almost or entirely vertical. The hinge connection as indicated at 22 is in a plane which is tangential to the roll. In addition the blade is so arranged that the free edge thereof engages the beater roll below the center thereof, and between the backfall 23 and the roll. Mechanism is provided for adjusting the free edge of the blade toward and from the roll. The said mechanism is in the form of screw rods 24, hinged at one end to the blade, and passing through fixed angle brackets 25 near the other end. The rod is engaged by a nut 26 on the opposite side of the bracket from the blade. It will be understood that a rod is provided at each end of the blade. With this arrangement, the blade cuts the stock clean from the roll, and there is no possibility of unbroken stock pushing the

blade out of place. With the blade arranged as above specified, it is possible to increase the height of the backfall, and to make a larger chamber in rear of the same.

The preferred form of beater roll is shown particularly in Figure 3. The roll is an integral construction, preferably of manganese steel, and it is provided with longitudinally extending blades 27, of substantially uniform thickness and inclined 70 or curved in a direction opposite to the direction of normal rotation of the beater roll. The curved construction of the blades assists in cutting the stock, and in propelling the same. Because of its integral construction and the strength of the material used, the roll may be made smaller than with the usual construction, and may be driven at a higher speed. The blades act upon the stock in somewhat the same manner as a 80 centrifugal pump, increasing the velocity 85 of the circulation, which is also increased by the high speed of the roll.

In normal operation, power is supplied to the motor 7 to drive spindle 4 directly and 90 rotates beater roll 3 in a clockwise direction as viewed in Fig. 3. The doctor blade 21 may be adjusted by turning the screw rod 24 so that the free end of the doctor blade will tick against the free cutting edges of 95 the blades 27 on the beater roll. The rotation of the beater roll causes the stock to circulate beneath the beater roll and be propelled over the backfall 23 and around the partition 2 to again pass beneath the beater 100 roll.

The use of a beater roll of a diameter smaller than is customary allows a greater number of revolutions per minute, and thereby makes possible the use of a high speed 105 electric motor. The cost of such a high speed motor is less than that of a low speed motor. There is, of course, complete elimination of line shafting, belts, etc. with much economy in power. When a group of beaters 110 are being driven by belts from line shafting in conformity with present standard practice, the clogging or breaking of one beater may necessitate shutting down the whole line of beaters, whereas with the construction 115 therein proposed each beater is a separate unit, and its motor switch can be opened without in any way interfering with other beaters. The present arrangement also makes possible a direct power reading on 120 each beater where that is desirable, and, of course, reduces friction loss, belt maintenance, lubrication cost, etc., as compared with more general practice. The efficiency 125 of circulation of stock is also greatly enhanced by the improved construction of the knives or blades 27 forming the outer periphery of the beater roll. These knives or blades are so curved as to cause the particles 130 of stock to be thrown by centrifugal force.

to the top of the blades and acquire a certain definite high velocity. This velocity together with the increased speed of rotation attained with my improved construction of beater roll bring about a far greater amount of circulation of stock than has heretofore been obtainable.

The improved form of doctor blade is approximately positioned to insure a clean cutting off of stock from the revolving beater roll, and bring about a better circulation of stock inasmuch as a larger chamber will be left over the backfall 23 as an aid to the increased efficiency in circulation of stock. The new form of doctor blade will not permit large chunks of stock to pass over the roll, but will cause them to recirculate before passing under the cutting edges of the blades on the beater roll.

I claim:

1. In combination, a beater roll and a motor having their axes in alignment, a connection between the motor and the roll for driving the same directly, said connection adapted to shear under a predetermined stress, and means for moving the motor and the roll vertically while retaining the aligned axes horizontal.

2. In direct driven beater roll, the combination with the roll and the motor connected therewith to drive the same directly, of means for simultaneously moving the motor and the roll vertically while holding the axes of the roll and motor horizontal.

3. In direct driven beater roll, the combination with the roll and the motor connected therewith to drive the same directly, of means for simultaneously moving the motor and the roll vertically while holding the axes of the roll and motor horizontal, and a frangible connection between the motor and the roll adapted to shear under a predetermined stress.

4. In direct driven beater roll construction, the combination with the roll and the motor, and the spindle upon which the roll is mounted, of means for supporting the motor and the adjacent end of the spindle, means for supporting the opposite end of the spindle, and means for simultaneously adjusting the two said supporting means vertically.

5. In direct driven beater roll construction, the combination with the roll and the motor, and the spindle upon which the roll is mounted, of means for supporting the motor and the adjacent end of the spindle, means for supporting the opposite end of the spindle, means for simultaneously adjusting the two said supporting means ver-

tically, and a frangible connection between the motor and the spindle adapted to shear under a predetermined stress.

6. In a beater construction, the combination of a back fall, a roll, and a doctor blade, the lower edge of said doctor blade extending below the crest of the back fall and adapted to engage the roll tangentially at a point slightly below the center of rotation of the roll.

7. In a beater construction, the combination of a back fall, a roll, and a doctor blade mounted to swing toward and from the roll, the lower edge of said doctor blade extending below the crest of the back fall and adapted to engage the roll tangentially at a point slightly below the center of rotation of the roll.

8. In a beater construction, the combination of a back fall, a roll, and a doctor blade hinged at its upper end and depending tangentially to the roll and mounted to move toward and from the roll, and means for adjusting the free edge of the blade toward and from the roll, the free edge of the blade extending below the crest of the back fall and being adapted to engage the roll slightly below the center of rotation thereof.

9. In beater construction, a roll having peripheral blades curved in the same direction to exert a propelling action on the stock, the blades having a substantially flat exterior surface terminating in a cutting edge, and a doctor blade adjustably mounted to move toward and from the roll and adapted to engage the roll tangentially.

10. In a beater construction, a beater roll adapted for propelling and disintegrating a pulp and having on its peripheral surface integral longitudinally extending blades curved in a direction opposite to the direction of normal rotation of the roll.

11. In a beater construction, a beater roll adapted for propelling and disintegrating a pulp and having on its peripheral surface integral longitudinally extending blades curved in a direction opposite to the direction of normal rotation of the roll, said blades having a substantially uniform thickness.

12. In a beater construction, a beater roll adapted for propelling and disintegrating a pulp and having on its peripheral surface integral longitudinally extending blades curved in a direction opposite to the direction of normal rotation of the roll, the free edges of said blades forming cutting edges.

In testimony whereof I affix my signature.
